UNITED STATES PATENT OFFICE.

WILLIAM H. SMITH, OF NEW BRITAIN, CONNECTICUT, ASSIGNOR TO LANDERS, FRARY AND CLARK, OF NEW BRITAIN, CONNECTICUT, A CORPORATION.

TABLE-CUTLERY.

No. 873,274.

Specification of Letters Patent.

Patented Dec. 10, 1907.

Application filed November 13, 1906. Serial No. 343,234.

To all whom it may concern:

Be it known that I, WILLIAM H. SMITH, a citizen of the United States, residing at New Britain, in the county of Hartford and State of Connecticut, have invented certain new and useful Improvements in Table-Cutlery, of which the following is a specification.

My invention relates to improvements in table cutlery, and the objects of my improvement are simplicity and economy of construction in the production of a durable and efficient article, of a neat and attractive appearance, particularly with reference to the union of the handle with the rest of the implement.

In the accompanying drawing:—Figure 1 is a broken side elevation of the middle portion of a table knife constructed in accordance with my improvement. Fig. 2 is a sectional side elevation of the same together with one part of the mold in which the bolster is cast. Fig. 3 is a sectional edge view on the line α α of Fig. 1. Fig. 4 is a detached side elevation of the handle, less its ferrule. Fig. 5 is a side elevation of the middle portion of a table fork constructed in accordance with my improvement.

The blade A, is provided with a flat tang 6 having notches 7 in its opposite edges. The handle B is provided with a tenon 8 to receive a ferrule 9 that is open for its full size at each end. The handle is centrally bored longitudinally from its smaller end to a depth fully equal to or a little in excess of, the depth that the tang 6 is to be inserted therein. The diameter of this bore 10, Figs. 2 and 3, is about equal to the width of the tang 6. The handle is also bored transversely at the tenon 8; through the central bore 10, thus forming the cross bore 11 shown in Figs. 3 and 4. The ferrule 9 is placed snugly on the tenon 8 so as to cover the ends of the cross bore 11. I prefer to make the tenon 8 a little longer than the ferrule 9 so as to effect a saving of metal in casting the bolster 12. After the parts are thus formed, the tang 6 is inserted to the proper depth in the handle B and the two together are placed in a suitable two part mold C having recesses 13 to receive the blade and handle with its ferrule, and also suitably shaped recesses to give form to the bolster 12 at a point between the tip end of the ferrule and heel of the blade, together with suitable sprue recesses 14 through which to fill the mold. Molten

metal is then run into the mold to form the bolster 12 and at the same time to fill the vacant space in the longitudinal and cross bore of the handle, whereby the filling 14 in the said bores is integral with the bolster and firmly secures the blade and tang within the said filling, and at the same time the combined tang and filling are locked within the handle at the cross bore 11. The cross bore being within the ferrule, the filling therein is concealed from view. After casting, the sprue 15 is removed and the bolster at that point smoothed off, thereby producing the product shown in Figs. 1 and 3. In Fig. 5, I have shown substantially the same handle B and ferrule 9, with a similar bolster 12^a and fork tang 6^a, all constructed as herein described for the knife in the other figures of the drawing.

I am aware that it is old to provide an implement with a flat tang having notches in its edges and to connect the same with a handle having a ferrule substantially closed at its tip end, the said handle having longitudinal and cross bores into which molten metal is poured through the said cross bore to firmly secure the filling and tang together and lock the combined tang and filling within the handle, and the same is hereby disclaimed.

In my improvement, the ferrule does not form the bolster, and the cross bore is within the ferrule so that it is wholly concealed in the finished article.

I claim as my invention:—

1. In table cutlery, the combination of a handle having longitudinal and cross bores with a ferrule on the end of the said handle in position to cover the ends of the cross bore, an implement having a flat tang inserted within the said longitudinal bore, and a combined bolster and filling formed of cast metal, the said bolster being outside of the tip end of the ferrule and forming the junction of the handle and implement, the filling at the cross bore being concealed by the said ferrule. 95

2. In table cutlery, a handle having a tenon at its smaller end, a closed or imperforate butt end, a longitudinal bore extending inwardly from its smaller end to the depth that the implement tang is designed to enter, 105 and a cross bore in the said tenon that extends into the central bore of the said handle, in combination with a ferrule open for its full size at each end and fitted upon the tenon of the said handle, an implement having a 110

notched tang with its major portion extended through the said ferrule, into and partly filling the said central bore of the said handle while a connecting portion of the said 5 tang remains between the body of the said implement and the smaller end of the said handle and outer end of the said ferrule, and a combined bolster and filling of cast metal with its bolster portion on the connecting

portion of the said tang between the body of 10 the implement and outer end of the ferrule and its filling portion around the said shank within the said handle and ferrule.

WILLIAM H. SMITH.
